C. W. HOMEYER

REFLECTOR HEATER

Filed Sept. 15, 1924

INVENTOR

C. W. Homeyer.
BY
G. J. Heinkel,
ATTORNEY

UNITED STATES PATENT OFFICE.

CHARLES W. HOMEYER, OF CLEVELAND, OHIO.

REFLECTOR HEATER.

Application filed September 15, 1924. Serial No. 737,716.

To all whom it may concern:

Be it known that I, CHARLES W. HOMEYER, a citizen of the United States, residing in Cleveland, county of Cuyahoga, and State of Ohio, have invented a new and useful Improvement in Reflector Heaters, of which the following is a specification.

My invention relates to heaters having a reflector back of the heating element to direct or reflect the heat waves produced by the heating element.

One of the objects of my invention is a simple and inexpensive reflector heater having the fewest possible parts.

Another object is to form these parts in the most simple manner.

Another object is to so arrange these parts that the heater can easily be assembled and taken apart.

Another object is to construct a reflector heater in two main units to facilitate assembling or taking apart and shipping.

Another object is to hinge these units to each other so that one unit can readily be swiveled or adjusted in relation to the other unit to permit the heat generated in the heater to be directed as desired.

Another object is to provide means on the hinge joint between the units to permit one unit to swivel or adjust in relation to the other and to remain in such adjusted position without manipulating any member of the hinge joint.

Another object is to provide a means to adjust the members of the hinge joint.

I attain my objects by the mechanism illustrated in the accompanying drawing in which:—

Fig. 1 is a rear perspective view of a reflector heater embodying the features of my invention, in one form, partly in section to show the members in relation to each other and the manner of securing the bracket to the heat reflector.

Fig. 2 is a section, taken on a horizontal plane indicated by the line 2—2 in Fig. 1, showing the hinge joint between the two units more clearly.

Similar reference characters refer to similar parts throughout the views.

The reflector heater shown in the accompanying drawing is composed of the reflector A, the bracket B, the heating element C, and the base D. The reflector A and the bracket B and the heating element C form one unit of the heater hereinafter called the

upper unit while the base forms a second unit hereinafter called the lower unit; these two units are hinged to each other.

The heat reflector A is dished as shown and has the corrugated flange 10 to stiffen the outer edge thereof and also has the flange 11 angular with the flange 10 to further stiffen the outer edge of the reflector. The flange 10 is provided with holes 13 into which the ends 12 of a wire screen 13 (illustrated by one wire only) are inserted.

The central portion of the bracket B conforms to the contour of the back of the dished portion of the reflector A and is provided with the hole 14 for the purpose appearing presently.

The upper end of the bracket B is formed with the handle 15 to carry the heater about.

The lower end of the bracket B is formed with the ears 16 and 17, forming a pair of ears, and each ear is provided with a hole for a hinge pin as will appear presently.

It is observed that the entire bracket is very simple and is formed of one piece of commercial stock, that the ears 16 and 17 are bent substantially at right angles to the main body of the bracket, and that the bracket can be formed in two or three punch press operations with comparatively simple dies.

The central portion of the reflector A is formed with a rearwardly extending projection 18, tubular in form, which extends through the previously mentioned hole 14 and is flanged or riveted over against the outside of the bracket B as shown at 19, thereby securing the bracket B to the back of the reflector A in a very economical manner.

It is observed that the reflector A is very simple, is made of one piece of inexpensive commercial stock, formable in one or two punch press operations with comparatively simple dies, and that the reflector and the bracket can very easily and economically be assembled and secured to each other by nothing more than the simple flanging or riveting operation previously mentioned.

The heating element C, in the present instance an electric heating element, is mounted on the insulation sleeve 20 which extends through the tubular projection 18.

Any other sort of heating element may be used.

It is observed that the heating element is easily installed in the reflector and that the

reflector and the bracket are easily formed and secured to each other as previously mentioned; therefore, the entire upper unit is simple of form and of composition of parts and therefore economical of manufacture.

The base D comprises the flange portion 21 and the upright portion 22 which has the flat faces 23 and 24 at the upper end thereof and the hole 25 traversing this upper end and these flat faces.

The ears 16 and 17 lay against the flat faces 23 and 24 respectively and the bolt 26 passes through these ears and through the opening 25.

15 The bolt 26 is provided with the cleat 27 adjacent the head 28. This cleat enters a suitable notch in the ear 16 and thereby prevents the bolt 26 from rotating or turning in the ears either when the wing nut 29 is manipulated or when the upper unit is 20 adjusted so that the bolt and the wing nut always rotate in unison with the reflector without changing their position in relation to the ears.

25 The wing nut 29 is threaded to the bolt 26 and bears against the ear 17 while the head 28 of the bolt 26 bears against the ear 16.

The wing nut 29 on the bolt 26, together 30 with the cleat 27 and the purpose thereof, forms an adjusting means for the swivel joint which permits the wing nut 29 to be set against the ear 17 with any desired pressure to create sufficient friction between the 35 ears and the faces 23 and 24 so that the upper unit may be swiveled or adjusted on the lower unit and remain in such position without manipulating the wing nut 29. This feature is quite advantageous in heaters 40 since they, usually, are adjusted when hot and it is quite inconvenient to handle hot objects particularly when more than two parts must be handled as in the present case.

45 When it is desired to lock the upper unit to the lower unit in any desired position, it is only necessary to tighten the wing nut 29 sufficiently tight to accomplish that purpose.

50 It is observed that all parts of the present heater, as shown, are in themselves very simple of structure; that the members of the upper unit are easily assembled and easily held together; and that the two units 55 are easily assembled and that one unit can easily be adjusted in relation to the other.

I am aware that changes may be made in the structure of the parts as well as in the arrangement thereof within the scope of the 60 appended claims; therefore, without limiting myself to the precise construction and arrangement of parts shown and described,

I claim:—

65 1. A reflector heater comprising, a heat reflector, a bracket mounted on said reflec-

tor to support the same on a base, the middle portion of said bracket contacting the back of said reflector and the rear portion of the heating element of the heater extending therethrough, the upper portion of said bracket bent outwardly, and the upper end of said bracket curved outward and downward to form a handle to carry the heater.

2. A reflector heater comprising, a base, a heat reflector, a bracket mounted on said reflector to support the same on said base, the middle portion of said bracket contacting the back of said reflector and the rear portion of the heating element of the heater extending therethrough, the upper portion 75 of said bracket bent outwardly, the upper end of said bracket curved outward and downward to form a handle to carry said heater, and the lower end of said bracket formed with hinge means to form a hinge joint between said base and said bracket.

3. A reflector heater comprising, a heat reflector, a bracket on the back of said reflector, and a portion of said reflector extending through said bracket and flanged over against the outside thereof to secure the same to said reflector.

4. A reflector heater comprising, a base, a heat reflector, a bracket on the back of said reflector and formed with means for 95 handling the heater and with hinge means to form a hinge joint between said base and this bracket, and a portion of said reflector extending through said bracket and flanged over against the outside thereof to secure 100 the same to said reflector.

5. A reflector heater comprising, a base, a heat reflector, a bracket on the back of said reflector and formed with means for handling the heater and with a pair of ears straddling a portion of said base to form a hinge joint between said base and this bracket, and a portion of said reflector extending through said bracket and flanged over against the outside thereof to secure 110 the same to said reflector.

6. A reflector heater comprising, a base, a heat reflector, a bracket on the back of said reflector, the upper end of said bracket formed with a handle and the lower end thereof formed with a pair of ears straddling the upper end of said base, a hinge pin through said ears and through said upper end of the base, and a portion of said reflector extending through said bracket and flanged over against the outside thereof to 115 secure the same to said reflector.

7. A reflector heater comprising, two units hinged to each other, one of said units provided with a pair of ears straddling a portion of the other of said units, a hinge pin through said ears and through said portion, means for adjusting said ears in relation to said portion, and means for retaining 125 said ears in adjusted position to permit 130

one of said units to be swiveled on the other of said units and to remain in the position swiveled into without manipulating said means for adjusting the ears.

8. A reflector heater comprising, a base having an upright portion, a dished heat reflector, and a bracket on the back of said reflector and dished less than said reflector to contact only the deepest portion of said reflector and one end thereof formed with a handle bent outward from said reflector to keep the handle cool and the other end thereof hinged to said upright portion.
10. A reflector heater comprising, a base

- 15 having an upright portion, a dished heat reflector, a dished bracket on the back of said reflector and one end thereof formed with a handle and the other end thereof hinged to said upright portion, and a portion of said 20 reflector extending through said bracket and flanged over against the outside thereof to secure said reflector to said bracket.

10. A reflector heater comprising, a base

having an upright portion, a dished heat reflector, a dished bracket on the back of said reflector and one end thereof formed with a handle and the other end thereof formed with a pair of ears straddling said upright portion, a hinge pin through said ears and through said upright portion, and means on 25 said hinge pin to adjust the friction between said ears and said upright portion.

11. A reflector heater comprising, a base having an upright portion, a dished heat reflector, a dished bracket on the back of 30 said heat reflector and one end thereof formed with a handle and the other end thereof formed with a pair of ears straddling said upright portion, a hinge pin through said ears and through said upright 35 portion, means on said hinge pin to adjust the friction between said ears and said upright portion, and means on said hinge pin to prevent the rotation thereof in said ears.

CHARLES W. HOMEYER.
